CHILD'S SPORTS CAR

Calvin Rouse, 87-26 166th St., Jamaica, N.Y.

Filed Feb. 26, 1960, Ser. No. 59,540

Term of patent 14 years

(Cl. D14—3)

Fig. 1 is a front perspective view of a child's sports car showing my new design;

Fig. 2 is a side elevational view thereof;

Fig. 3 is a rear perspective view thereof taken diagonally opposite from Fig. 1.

I claim:

The ornamental design for a child's sports car, substantially as shown.
